COMBINED BOAT, TRAILER, KITCHEN UNIT
AND ENCLOSED CARRIER

Morton W. Johnson, 521 E. Longview Ave.,
Stockton, Calif.

Filed May 28, 1963, Ser. No. 75,107

Term of patent 3½ years

(Cl. D14—3)

Fig. 1.

Fig. 2.

FIG. 3.

FIG. 4.

FIG. 6.

FIG. 5.

FIG. 1 is a bottom, right, front perspective view of a combined boat, trailer, kitchen unit and enclosed carrier, showing my new design;

FIG. 2 is a top, right, rear perspective view;

FIG. 3 is a top plan view;

FIG. 4 is a left side elevational view;

FIG. 5 is a front elevational view; and

FIG. 6 is a rear elevational view thereof.

I claim:

The ornamental design for a combined boat, trailer, kitchen unit and enclosed carrier, as shown.
